(57) **CLAIM**

The ornamental design for a buckle for headlamp, as shown and described.

DESCRIPTION

FIG. 1 is a front elevational view of a buckle for headlamp, showing the new design;

FIG. 2 is a rear elevational view thereof;

FIG. 3 is a left-side elevational view thereof;

FIG. 4 is a right-side elevational view thereof;

FIG. 5 is a top plan view thereof; and,

FIG. 6 is a bottom plan view thereof.

The broken lines in the drawings represent portions of the buckle for headlamp and form no part of the claimed design.
